UNITED STATES PATENT OFFICE.

CHARLES D. McARTHUR, OF PITTSBURGH, PENNSYLVANIA, ASSIGNOR TO THE BLAW COLLAPSIBLE STEEL CENTERING COMPANY, OF PITTSBURGH, PENNSYLVANIA, A CORPORATION OF NEW JERSEY.

COLLAPSIBLE TELESCOPING FORM.

1,108,201.

Specification of Letters Patent. Patented Aug. 25, 1914.

Application filed November 3, 1910. Serial No. 590,567.

To all whom it may concern:

Be it known that I, CHARLES D. McARTHUR, a citizen of the United States, residing at Pittsburgh, in the county of Allegheny and State of Pennsylvania, have invented certain new and useful Improvements in Collapsible Telescoping Forms, of which the following is a specification.

The invention relates to collapsible forms for use in forming conduits, sewers and the like, and particularly to those so arranged that the various sections employed may telescope one within another so that the sections may be carried forward to position through a series of sections in operative position and upon which the concrete is setting. The objects of the invention are; the provision of telescoping sections in which means are provided for slidably supporting the collapsed sections as they are brought forward through the expanded sections; the provision of a circular collapsible form in which improved means are provided for permitting the collapse of the sections; the provision of an improved form of rigid self supporting form wherein the interior of the form when in expanded operative position is free and unobstructed to permit of the passage of other sections therethrough; and the provision of a telescoping construction in which the various sections may be forwarded from one position of use to another with a minimum expenditure of effort and without the necessity of using carrying devices, trucks or the like. One embodiment of the invention is illustrated in the accompanying drawings, wherein:—

Fig. 1 is an end view of one of the sections employed, the full lines indicating the expanded or operative position of the parts, and the dotted lines indicating the collapsed position of the parts, and Fig. 2 is a longitudinal section through the construction.

In the drawings only one section is shown completely, but it will be understood that in practice a plurality of sections placed end to end and detachably secured together are employed, the sections being detachably secured together by means of bolts indicated in Fig. 2. It will also be understood that in operating the form, the rear sections are successively collapsed and brought forward through the sections upon which the concrete is hardening and secured in position at the

front end of the form, so that the operation is substantially a continuous one.

As indicated in Fig. 2 each section is provided with stiffening ribs, 1, 2 and 3, although the number may vary depending upon the conditions, and that sheet metal lagging 4 is secured to the outer side of the stiffening ribs. The stiffening ribs are preferably channel bars, although obviously other sections might be employed, and are of sufficient rigidity to rigidly and securely support the lagging against the pressure of the concrete when the parts are in expanded position without the necessity of employing any transverse braces, the interior surface of the form being thus left entirely free and unobstructed for the passage of other sections. As indicated in Fig. 1 the lagging and ribs are cut along the lines 5 and 6 in order to provide the flaps or wings 7 and 8, such wings being hinged to the main portion of the form by means of the hinges 9. The swinging of these wings down to the position indicated in dotted lines in Fig. 1 permits of the collapsing of the main portion of the form, such collapsing being effected by means of the turn-buckles 10 extending transversely of the form and detachably secured to the ribs at their ends by means of the bolts 11. The wings are held against swinging movement when in open position by means of the hooks 12. The two wings 8 and 9 are preferably used instead of a single longer wing, as the two wings are more easily detached and secured in open position and occupy less space during the swinging movement, than does a single wing. Additional vertical turnbuckles 19 may also sometimes be employed to hold the section collapsed.

In order to permit of the ready movement of the collapsed sections through the other sections, the sets of rollers 13, 14 and 15 are provided, which rollers are secured to the ribs by means of the clips shown in Fig. 2. From Fig. 1 it will be seen that when the section is collapsed it fits freely inside of another section, and that the rollers 13, 14 and 15 will support the exterior surface of the collapsed section and permit its ready movement through the expanded sections. As indicated in Fig. 2 the sections are secured detachably together by means of the bolts 16, which pass through the flanges of the chan-

nels 1 and 3 and through the flanges of the channels 17 and 18 constituting the end ribs upon other sections of the form which are precisely the same in construction and operation as the one heretofore illustrated and described.

The invention is of course not limited in its application to forms which are of the true circular cross section shown, and it will be 10 understood that the term circular as employed is used in its generic sense to designate complete mold sections as opposed to the incomplete forms of inverted U cross section open at the bottom. It will also be 15 understood that the invention is not limited to the use of the two wings 7 and 8, although this is the preferred construction.

Having thus described my invention and illustrated its use, what I claim as new and 20 desire to secure by Letters Patent is the following:—

1. In combination in a collapsible mold, supporting ribs covered with lagging and comprising main rib portions, and relatively 25 short portions hinged to the ends thereof with knuckle joints so as to swing inwardly, and lying at the top of the mold, the said ribs being sufficiently yielding to spring inwardly when the hinged portions are 30 swung inwardly, but sufficiently stiff to maintain the mold in expanded position leaving the interior of the mold unobstructed when the hinged portions are in their outer operative position.

2. In combination in a collapsible mold, 35 supporting ribs covered with lagging and comprising main rib portions, and relatively short portions hinged to both ends of each main rib with knuckle joints so as to swing inwardly but not outwardly past operative 40 position, the said ribs being sufficiently yielding to spring inwardly when the hinged portions are swung inwardly, but sufficiently stiff to maintain the mold in expanded position 45 leaving the interior of the mold unobstructed when the hinged portions are in their outer operative position.

3. In combination in a collapsible mold, supporting ribs covered with lagging and comprising main rib portions, and relatively 50 short portions hinged to the ends thereof and constructed to swing inwardly from operative position but not outwardly past such position, the said ribs being sufficiently yielding to spring inwardly when the hinged 55 portions are swung inwardly, but sufficiently stiff to maintain the mold in expanded position leaving the interior of the mold unobstructed when the hinged portions are in their outer operative position.

In testimony whereof I have hereunto signed my name in the presence of the two subscribed witnesses.

CHARLES D. McARTHUR.
